UNITED STATES PATENT OFFICE.

EMIL SALTZKORN AND LUDWIG NICOLAI, OF DRESDEN, GERMANY, ASSIGNEES TO THE AMERICAN METAL EDGE BOX COMPANY, OF CAMDEN, NEW JERSEY, AND PHILADELPHIA, PENNSYLVANIA.

DESIGN FOR AN EYELET.

SPECIFICATION forming part of Design No. 32,147, dated January 30, 1900.

Application filed July 17, 1899. Serial No. 724,198. Term of patent 14 years.

To all whom it may concern:

Be it known that we, EMIL SALTZKORN and LUDWIG NICOLAI, subjects of the Emperor of Germany, and residents of Dresden, Germany, 5 have invented and produced a new and original Design for Eyelets, of which the following is a specification.

Our design for an eyelet or fastening is clearly illustrated in the accompanying drawings, in which—

Figure 1 is a side view of the eyelet. Fig. 2 is a sectional view, and Fig. 3 is a perspective view showing the eyelet.

The essential feature of the design is the eyelet having arrow-head projections, as clearly 15 illustrated in the drawings.

A is a piece of metal from which the eyelet is formed.

a are the prongs. Each projecting prong

is tapered and is slightly curved. The prongs 20 are undercut near the point where they join the metal, so that each prong is in the form of an arrow-head.

We claim—

The design for an eyelet as herein described 25 and as shown in the accompanying drawings.

In testimony whereof we have signed our names to this specification in the presence of two subscribing witnesses.

EMIL SALTZKORN.
LUDWIG NICOLAI.

Witnesses as to Emil Saltzkorn:

HERNANDO DE SOTO,
PAUL ARRAS.

Witnesses as to Ludwig Nicolai:
